UNITED STATES PATENT OFFICE.

JOHN P. McCAVITT, OF FALL RIVER, MASSACHUSETTS, ASSIGNOR OF ONE-HALF TO
RICHARD WADDICOR, OF FALL RIVER, MASSACHUSETTS.

SPINNING FRAME AND CAM.

Application filed May 17, 1922. Serial No. 561,779.

To all whom it may concern:

Be it known that I, JOHN P. McCAVITT, a citizen of the United States, and a resident of Fall River, in the county of Bristol and 5 State of Massachusetts, have invented a new and Improved Spinning Frame and Cam, of which the following is a full, clear, and exact description.

This invention relates to an apparatus for 10 spinning yarn and particularly to an improved cam and associated spinning frame, the construction being such that the spindles on the frame are adapted to receive an extra large supply of yarn.

15 The object of the invention is to provide a simple, effective construction which will operate substantially in the usual manner but which will produce an increased yardage in the yarn wound on the spindles of the 20 device.

Another object in view is to provide an improved cam interposed in the driving mechanism of the spinning frame whereby 25 a slow and fast motion may be secured to permit an extra supply of yarn to be wound on the spindles at a desired point.

In the accompanying drawing—

Figure 1 is a fragmentary side view of a 30 spinning frame with a cam associated therewith, the same disclosing one embodiment of the invention.

Figure 2 is an enlarged side view of the 35 cam and associated parts shown in Figure 1, said cam being shown in a different position.

Figure 3 is an edge view of the structure shown in Figure 2.

Referring to the accompanying drawing by numerals, 1 indicates spindles of any desired kind which are supported in any suitable or usual manner and rotated in any usual manner when the frame 2 is in operation. This spinning frame is of the usual construction and in fact all of the parts 40 shown in Figure 1 are of the usual construction except the cam 3 and wheel 5 and the way the same are associated with the other parts including the way the chain 4 is mounted as well as the way the wheel 5 is connected 45 with chain 6. In spinning frames of this kind, a rail 7 is provided which travels up and down for guiding the yarn as it is wound on the spindles 1. One or more rods 8 may be used for causing the rail 7 to travel upwardly, said rail moving downwardly usual- 50

ly under the action of gravity. The various rods 8 are guided in any suitable manner in the frame 2 and are provided with enlarged feet 9 at the lower end for engaging the end of the operating lever 10. This operating lever is connected in any suitable manner with the lever 11 pivotally mounted at 12 on the bracket 13.

The lever 11 is connected in any suitable manner to a rod or cable 14 and as said rod or cable is moved longitudinally, movement will be transmitted to the various parts including the rod 8 for elevating the same or permitting the same to be moved downwardly. The lever 11 and rods 8 are preferably 60 arranged at suitable distances along the frame 2 so that the rail 7 will be moved upwardly and will remain horizontal. Where this movement is an even and regular up and down movement, a certain amount 65 of yarn is wound on the spindles. Heretofore, this even up and down movement was provided by connecting chain 6 directly to the lever 11'. Suitable well known mechanism not shown on the drawing operates the 70 rod 15 to move the same back and forth and this mechanism, not shown, usually causes the rail 7 an up and down movement of about one and three quarter inches and then increases this movement as the spindles begin to fill.

In the present instance, the wheel 5 and the cam 3 have been interposed between the rod 15 and the lever 11' so as to secure a slow movement of the rail 7 at the lower 75 part of the spindles 1 and then gradually quicken the movement at the upper part whereby a larger number of yards of yarn may be wound on each spindle.

As indicated in Figures 1 and 2, the wheel 80 5 is mounted on a suitable shaft 16 and the periphery is circular, said wheel being connected at 17 to the chain 6 so that when the chain 6 is moved the wheel will be rotated 85 for part of a revolution. Rigidly secured to the shaft 16 is the cam 3 which is arranged in the position shown in Figure 1 when the rail 7 is arranged as shown in Figure 1 while the parts will assume the position 90 shown in Figure 2 when the rail 7 is moved to its uppermost position. When the up and down travel of the rail 7 is begun, said travel is usually one and three eighth inches 95 though it could be any desired number of 100 inches and this travel is continually and 105 110

gradually increased at every trip of the rail 7 until the bobbin is full and the travel of the rail has increased to one and three quarter inches.

5 The provision of the cam 3 causes the speed of the rail 7 to increase as the cam turns over and the chain 4 engages part of the cam at a larger diameter. It is to be noted that when the device first starts, the 10 cam and associated parts are in the position shown in Figure 1, namely, at the smallest diameter of the cam and as the wheel 5 rotates cam 3 will also rotate. The first part of the rotation will cause the rail 7 to move 15 gradually upward at substantially an even speed but as the chain 7 begins to engage the larger diameter of the cam the speed will gradually increase until the parts assume the position shown in Figure 2. As the cam 20 reverses its movement, the speed of downward travel of the rail 7 will be comparatively fast and will gradually decrease in speed until it reaches its lowermost position. In this way, the movement of rail 7 near the 25 lower ends of the spindles will be slow and near the upper ends will be fast so that a larger amount of yarn will be wound at the lower end of the spindles and, consequently, a properly formed bobbin will be 30 the result. Without the use of the cam 3 the

movement of the rail 7 will be uniform and, consequently, only a certain amount of yarn could be wound on the spindles while the use of the cam 3 permits a larger amount to be wound, said larger amount being ar- 35 ranged near the base of the spindle.

What I claim is:—

The combination with an actuating rod adapted to raise the yarn guiding frame of a spinning machine, a shaft rotatably mounted 40 on the frame of said spinning machine, a disk secured to said shaft, an eccentrically mounted cam acting disk secured to said shaft, a flexible pulling element connected to the first mentioned disk and adapted to 45 be wound thereon, said pulling element being adapted to rotate said first mentioned disk, said shaft and the second mentioned disk, a flexible pulling element connected to the second mentioned disk and adapted to be 50 wound thereon, a reciprocating bar connected to the opposite end of said second mentioned pulling element, said bar being actuated by said second mentioned pulling element as said eccentrically mounted cam disk 55 rotates, and means operated by said bar for raising said actuating rod and said guiding frame.

JOHN P. McCAVITT.
